UNITED STATES PATENT OFFICE.

CARL W. WEISS, OF BROOKLYN, NEW YORK.

IGNITING DEVICE FOR INTERNAL-COMBUSTION ENGINES.

1,284,842.

Specification of Letters Patent. Patented Nov. 12, 1918.

Application filed October 24, 1917. Serial No. 198,290.

To all whom it may concern:

Be it known that I, CARL W. WEISS, a citizen of the United States, residing in the borough of Brooklyn of the city of New York, in the State of New York, have invented certain new and useful Improvements in Igniting Devices for Internal-Combustion Engines, of which the following is a specification, reference being had to the accompanying drawings, forming a part hereof.

Spark igniters are not available for use in starting up internal combustion engines which use kerosene or heavier fuel oils. It has been proposed to use for this purpose incandescent wire igniters, maintained at the necessary temperature by the passage of an electric current. Ignition has also been effected by successive compressions within the explosion chamber, particularly in connection with internal igniting devices which become highly heated through repeated compressions of the charge. For the most part, however, the initial heating necessary for the starting up of engines of this type is accomplished by the use of external heat applied to some part of the cylinder head, this method of ignition being slow and adapted mainly for use with stationary engines. It is the object of this invention to provide an igniting device for starting engines of the type referred to which shall be simpler and quicker in operation than the usual blow-torch igniter, shall be quicker than the compression method, and shall not require the use of an electric current. In accordance with the invention there is provided in the head end of the cylinder, adjacent to a controllable port, an igniting body of a suitable heat resisting material such as nichrome wire or spongy platinum, which is capable of quickly becoming heated, by a flame drawn in through such port, when it is open, from a suitable burner placed outside the cylinder wall, to a temperature sufficient to effect the ignition of the fuel oil introduced into the cylinder, and is capable also of retaining heat sufficient to continue ignition after the engine is started and the external flame is cut off. The invention will be more fully explained hereinafter with reference to the accompanying drawing in which it is illustrated and in which,—

Figure 1 is a view partly in longitudinal section and partly in elevation of the cyl-

inder of an internal combustion engine 55 equipped with the improved igniting device.

Figs. 2 and 3 are detail views, in vertical section and in horizontal section respectively, through an igniting device of the same character as that shown in Fig. 1 but of slightly 60 different form.

Fig. 4 is a detail view in vertical section of another form of the igniting device.

Fig. 5 is a detail view in vertical section of a form of the igniting device adapted for 65 use with a vertical cylinder.

The improved igniting device is capable of application to an internal combustion engine cylinder in which any of the heavier fuel oils is employed. It is shown in Fig. 1 70 as applied to a horizontal cylinder *a*, provided as usual with a water jacket *b*, a fuel oil inlet *c*, exhaust ports *d*, air inlet ports *e*, and a reciprocating piston *f*. The cylinder is shown as having a somewhat elongated 75 compression space and as having in the end of such compression space an igniting body *g* which is represented as taking the form of a wire cage, made of a heat resisting material, such as nichrome 80 wire or platinum. The cylinder or its compression space is provided also with a port *h* which opens externally of the cylinder and communicates internally directly with the space occupied by the igniter body 85 *g*. The port is controlled by a hand-operated valve plug *k*, which is shown in Figs. 1, 2, 3 and 4 as threaded into a suitable support therefor and is provided with a suitable handle *k'*.

In the embodiment of the invention illustrated in Fig. 4 the valve plug is of another ordinary type having a seat in the extension *a'* of the cylinder head, between the inner and outer ends of the port or passage *h*. 95 Located externally of the cylinder and in suitable proximity to the port or passage *h*, is a burner, that is, an external source of flame. This burner may be of any convenient character. As shown in Fig. 1, it comprises a pocket *a''*, open at the sides and adapted to receive a wad of asbestos *a'''*, which may be saturated with alcohol or oil to be ignited by a match and furnish a flame for a short time. In the construction shown 100 in Figs. 2 and 3 the burner is of the same character as that shown in Fig. 1, but of a slightly different form. In the construction 105

shown in Fig. 4 the burner is also of the same character but arranged in a somewhat different way. In the construction shown in Fig. 5 the pocket a^2 is an annular pocket surrounding the port or passage h and the valve plug k on the top of a vertical cylinder.

In the operation of the improved igniting device the port or passage h is opened by the valve plug k , the burner is ignited, and the engine is turned over a few times by hand. The flame from the burner is drawn into the cylinder, through the igniting body, in each forward movement of the piston and at the same time the fuel injection pump is operated, air is taken in, and a fuel mixture is formed in the cylinder. So long as the port h remains open the fuel mixture is expelled at each rearward movement of the piston, but at each operation the igniter body becomes more highly heated and presently attains a temperature sufficient to ignite the mixture. The port is then closed and with the added heat due to compression ignition of the charge continues and the engine operates and comes up to normal speed. It will be observed that as there is no external hot surface, as in the ordinary hot ball igniter, the whole cylinder head can be well water jacketed, the heat retained by the igniter body being sufficient to keep the engine in operation at normal speed, even when it is running idle. It will be understood that the burner, whatever its character, should be so located with respect to the port or passage h that in starting up the flame shall not be extinguished by the blast of air from the port during the rearward movement of the piston.

Various changes in details of arrangement can be made to suit different conditions of use or the convenience of the manufacturer and the invention, therefore, is not limited to the particular construction shown and described herein.

I claim as my invention:

1. An igniting device for an internal combustion engine, comprising a cylinder having a port or passage providing communication between the compression space and the external air, means to control the port or passage, a heat resisting igniter body located within the compression space adjacent to such port or passage, and a source of flame located outside of the cylinder adjacent to said port or passage, whereby, when the engine piston moves forward and the port is open, flame from such source is drawn through the port and into contact with the igniter body to heat the same. 45

2. The combination with an internal combustion engine cylinder having a controllable port opening externally of the cylinder and communicating internally with the compression space of an igniter body located within the compression space adjacent to said port, 60 and a source of flame located outside of the cylinder adjacent to said port, whereby, when the engine piston moves forward and the port is open, flame from such source is drawn through the port and into contact 65 with the igniter body to heat the same. 70

3. The combination with an internal combustion engine cylinder having a controllable port opening externally of the cylinder and communicating internally with the compression space of an igniter body, of heat resisting material located within the compression space adjacent to such port, and a burner located outside of the cylinder adjacent to such port, whereby, when the engine piston moves forward and the port is open, flame from said burner is drawn through the port 75 and into contact with the igniter body to heat the same. 80

This specification signed this 22d day of 85 Oct., 1917.

CARL W. WEISS.
